UNITED STATES PATENT OFFICE.

JAMES M. WILSON, OF NEWARK, NEW JERSEY.

MAGNETIC INDUCTOR

1,308,567.

Specification of Letters Patent. Patented July 1, 1919.

Application filed January 5, 1917. Serial No. 140,677.

To all whom it may concern:

Be it known that I, JAMES M. WILSON, a citizen of the United States, and a resident of the city of Newark, county of Essex, and 5 State of New Jersey, have invented certain new and useful Improvements in Magnetic Inductors, of which the following is a specification.

My invention relates more particularly to 10 a battery or direct current magnetic inductor in which a battery current or direct current from other source is adapted to energize pole pieces symmetrically arranged about a rotary member carrying suitable 15 magnetically insulated inductors. Suitably spaced between the poles of the battery magnet or magnets I preferably mount other pole pieces forming the ends of a soft iron core or cores surrounded with primary 20 and secondary coils, the induced current of the secondary coil being adapted to be utilized at the spark plugs of an internal combustion engine.

The object of my improved device is to 25 more efficiently utilize a direct current for ignition purposes and to insure a better spark for less current than ordinarily obtained from a battery, and also to eliminate the destructive burning of breaker points 30 by using them in circuit with induced alternating current instead of having, as is usual, the battery or direct current directly in series with the breaker or contact points.

I have also provided a switch for breaking 35 the circuit of the battery through the battery coils and for sending the current through the primary coils temporarily when starting the engine.

One form of my invention is shown in the 40 accompanying drawings, in which—

Figure 1 represents a side elevation of the device.

Fig. 2 represents a central vertical section through the induction coils.

Fig. 3 represents a plan view with the top cover removed.

Fig. 4 represents a transverse section on the line 4—4 of Fig. 2; and

Fig. 5 represents diagrammatically the electrical connections of the device.

Referring to the drawings, 1 represents the lower circular base plate provided with a central boss 2 having a hole therethrough

adapted to serve as the bearing for one end of the shaft 3. Another circular frame plate 4 is located above the base plate 1 and spaced therefrom by suitable tubes 5 (see Fig. 4), the two plates being held rigidly together by screw rods 6. The plate 4 is also provided with a central opening through which the small end of the shaft 7 projects, the plate 4 acting as a bearing for this end of the shaft. Symmetrically arranged around the central shaft 7 are four magnets each with a crescent-shaped pole piece at each end. Two of the magnets are battery magnets and comprise soft iron cores 8 and 9 surrounded by coils 10 and 11. To each end of the cores 8 and 9 are secured similarly shaped pole pieces 12 and 13 cut away on their inner faces so as to appear crescent-shaped, as seen in Fig. 4 of the drawings. The pole pieces 12 and 13 are rigidly secured to the cores 8 and 9 by screws or other suitable means and the straight electromagnets thus formed are secured between the upper frame plate 4 and the base plate 1 and permanently held in proper position by suitable screws 14, as indicated in the drawings.

In a plane at right angles to the plane of the battery magnets I preferably mount another pair of soft iron cores 15 and 16, which in the present instance are represented as laminated. It will be understood, however, that one or both sets of magnet cores may be laminated, if desired. The induction cores 15 and 16 are likewise provided with pole pieces 17 and 18 which are cut away on the inside to leave the crescent form substantially identical with the pole pieces attached to the cores of the battery magnets. Each of the cores 15 and 16 is surrounded by a primary coil 19 and a secondary coil 20. These induction magnets are similarly secured between the base plate 1 and the upper frame plate 4 by suitable screws 21, the whole arrangement being adapted to rigidly secure the parts in position.

On the upper and lower ends of the smaller shaft 7, adjacent the plates 1 and 4, respectively, as indicated in Fig. 2 of the drawings, I preferably secure thereto a pair of disks 22 and 23 spaced apart by hubs 24 through which pins 25 are passed for se-

curing the disks to the shaft 7. The disks are thus spaced apart and between them at each end I secure a pair of inductors 26 and 27 preferably built up of laminated soft iron segmental plates. Each pair of inductors is adapted to lie in the plane of the pole pieces 12, 13, 17 and 18 at each end of the magnet cores. The inductors are arc-shaped and not quite a complete semi-circle in length, as indicated in Figs. 4 and 5 of the drawings. The disks 22 and 23 are preferably of brass or other suitable material for magnetically insulating the inductors.

15 The upper end of the shaft 7 is preferably provided with a four-lobed cam 28 secured to the shaft by a suitable screw 29, the cam being preferably of insulating material carried upon a metal collar or bushing 30, as indicated in Figs. 2 and 3 of the drawings.

20 The inner ends of the battery coils 10 and 11 are preferably connected together and one of the outer ends 31 is preferably connected to the ground in any suitable manner, as through the switch 32, as represented in Fig. 5 of the drawings. The other end 33 of the battery coil is connected with the battery, the latter being connected to the ground, as indicated in Fig. 5 of the drawings. The primary windings 19 on the cores 15 and 16 are connected together at their inner ends by connections 34, as indicated in Fig. 5, one outer end 35 being connected to the switch pivot 36, while the other end 37 is connected to an insulated contact post 38 bearing a contact point 39 adapted to coöperate with a point 40 on an interrupter 41, diagrammatically shown in Fig. 5 and more specifically shown in Fig. 3 of the drawings. The interrupter lever 41 is connected by a suitable connection 42 with the ground. Specifically, the interrupter lever 41 is pivotally mounted upon the upper plate 4 by means of a screw 43, the lever being preferably insulated from the plate 4, the ground connection with the lever being made through the wire 42, as indicated in Fig. 3 of the drawings. The lever 41 is preferably a bent arm lever, one arm being provided at 44 with an insulated plate adapted to coöperate with the points of the four-lobed cam 28, substantially as indicated in Fig. 3. A spring 45 is adapted to press 45 against the arm of the lever 41 and hold the contact points 39 and 40 in contact, so as to close the circuit of the primary coil except as it is interrupted by the lobes of the cam block 28. Since the cam block 28 is secured to the upper end of the shaft 7 and revolves therewith the interruption of the primary circuit will occur periodically, and the position of the points of the cam-lobes are adjusted to cause the interrupter lever 41 to be operated to break the primary circuit at

the point of maximum inductive effect of the inductors 26 and 27.

In order to reduce the break spark at the contacting points 39 and 40, I preferably connect a condenser 46 between the terminal 38 and the ground, as indicated in Figs. 3 and 5 of the drawings. One end of the condenser is connected by a wire 47 with the terminal 38, while the other end of the condenser is connected by means of a wire 48 75 with the ground in any suitable manner.

The secondary coils 20 have their inner ends connected together by a suitable cross-over connection 49, while one end of the secondary circuit is connected to the ground 80 at 50, as indicated in Fig. 5 of the drawings. The other end of the secondary circuit is connected by a suitable wire 51 with a rotor which, in the present instance, comprises a disk 52 of insulating material provided with 85 a metal bushing 53 by which it is attached to the upper end of the shaft 7 just above the four-lobed cam block 28, as indicated in Fig. 2 of the drawings. The disk 52 is preferably provided with an annular ring 90 54 with which a brush 55 coöperates, the brush projecting upward through an insulated block 56, as indicated in Figs. 2 and 3 of the drawings. The brush 55 is connected by means of the wire 51 with one end 95 of the secondary coils substantially as diagrammatically illustrated in Fig. 5 of the drawings. Another brush 57 is electrically connected with the annular ring 54 and projects through the rotor, as indicated in Fig. 100 2 of the drawings, and is adapted to contact with four contact pieces 58 arranged in the four quadrants of the circle of rotation of the brush 57. The contact pieces 58 are adapted to be connected with the four spark 105 plugs 59 in any suitable or preferred manner, as indicated in Fig. 5 of the drawings. The contact pieces 58 are preferably embedded in insulating material secured to or forming the cap or cover 50 for the upper 110 portion of the apparatus. The lower portion of the apparatus is preferably inclosed by a cylindrical cover 61 of insulating material. The contact pieces 58 preferably coöperate with plugging in contacts 62 115 formed in bosses 63 projecting from the outer surface of the cover plate 60, as indicated in Figs. 1 and 2 of the drawings.

The device may be mounted adjacent to the engine in any suitable manner, it being 120 understood that the shaft 3 is connected with or adapted to rotate at the same speed as the cam shaft of the four-cylinder engine with which the device is to be used. The spark plugs are then connected with the 125 contact pieces 58, the connections being such as to give the proper sequence in firing the cylinders. When the engine is running the shaft 3 will be rotated and at each quarter of a turn thereof the interrupter 41 will 130

be rocked by the lobed cam 28 to break the primary circuit at the maximum of induction thereby discharging through the rotor and one of the contact pieces 58 the secondary current which will produce the necessary spark across the spark plug to cause ignition in the cylinder. The battery circuit under these conditions is normally closed through the ground connections, the switch arm 36^a in that case being thrown over to the lower position (as indicated in Fig. 5 of the drawings, the switch arm is in between the contact), so as to ground not only the battery circuit from the wire 31, but also the primary through the wire 35, in the manner previously described.

I have found it desirable in starting the engine to direct the battery current through the primary circuit instead of through the magnet coils 10 and 11 thus providing for direct induction in the secondary coils. This I accomplish by moving the switch arm 36^a up to the contact point 64, which, as will be seen in Fig. 5 of the drawings, is connected by a wire 65 with the battery 66. After the engine has started the switch arm 36^a is thrown down to the lower position and thereafter the battery current will flow through the battery coils and energize the electro-magnets.

In the form of apparatus shown and described, I have adapted the device to a four-cylinder engine, but obviously the same principle may be applied to other types of engines—such as six-cylinder—in which case the number of inductors and magnets may be varied to suit the conditions, the method of doing this being well understood by those skilled in the art. It is also obvious that various modifications in the arrangement and number of coils may be made to obtain similar results without departing from the spirit and scope of the invention I have herein described. By the use of the word battery in the claims, I intend to include any suitable source of direct current.

I claim:

1. A battery magnetic inductor comprising an electro-magnet provided with pole pieces, a battery coil for energizing the same, a soft iron core provided with pole ends located between said electro-magnet pole pieces, primary and secondary coils about said core, a pair of magnetically insulated rotary inductors adapted to direct the magnetic flux through said core alternately in opposite directions, an interrupter in circuit with said primary coil and a multilobed cam rotating with said inductors for intermittently actuating said interrupter.

2. A battery magnetic inductor comprising a pair of straight electro-magnets on opposite sides of a rotary member, pole pieces at each end of said magnets, battery coils for energizing said pole pieces, a pair

of soft iron cores symmetrically arranged between and parallel with said electro-magnets, pole pieces at each end of said cores, primary and secondary coils about each of said cores, the circuit of the primary coils being closed by grounding, one end thereof being adapted to be connected to and grounded simultaneously with one end of said battery coils, a pair of magnetically insulated inductors at each end of said rotary member adapted to direct the magnetic flux from the pole pieces of said electro-magnets through said cores alternately in opposite directions, and an interrupter in circuit with said primary coils whereby the primary circuit may be broken intermittently.

3. A battery magnetic inductor comprising a pair of straight electro-magnets on opposite sides of a rotary member, pole pieces at each end of said magnets, battery coils for energizing said pole pieces, a pair of soft iron cores symmetrically arranged between and parallel with said electro-magnets, pole pieces at each end of said cores, a pair of magnetically insulated inductors at each end of said rotary member adapted to direct the magnetic flux from the pole pieces of said electro-magnets through said cores alternately in opposite directions, an interrupter in circuit with said primary coils, and a multilobed cam rotating with said rotary member for intermittently actuating said interrupter.

4. A battery magnetic inductor comprising a pair of straight electro-magnets on opposite sides of a rotary member, pole pieces at each end of said magnets, battery coils for energizing said pole pieces, a pair of soft iron cores symmetrically arranged between and parallel with said electro-magnets, pole pieces at each end of said cores, primary and secondary coils about each of said cores, a pair of magnetically insulated inductors at each end of said rotary member adapted to direct the magnetic flux from the pole pieces of said electro-magnets through said cores alternately in opposite directions, contact pieces arranged in the quadrants of a circle about the axis of said rotary member, a rotor secured to said rotary member carrying a brush adapted to cooperate with said contact pieces, means for connecting said secondary coils with said rotor, and means for interrupting the primary circuit at the time of maximum inductive effect of said inductors.

5. A battery magnetic inductor comprising a pair of electro-magnetic pole pieces, a battery coil for energizing the same, a soft iron core with pole ends symmetrically arranged with respect to said electro-magnetic pole pieces, primary and secondary coils about said core, the circuit of said

primary coil being closed by grounding, a rotary inductor adapted to direct the magnetic flux through said core alternately in opposite directions, a switch for normally connecting the primary circuit to one end of said battery coils and simultaneously grounding both coils, the switch being

adapted for breaking said grounding connection and connecting said primary coil directly with the battery and an interrupter in circuit with said primary coil whereby the primary circuit may be broken intermittently. 10

JAMES M. WILSON.
